UNITED STATES PATENT OFFICE.

WILLIAM J. BORLASE, OF PHILADELPHIA, PENNSYLVANIA.

BAG HOLDER.

Application filed April 4, 1923. Serial No. 629,848.

To all whom it may concern:

Be it known that I, WILLIAM J. BORLASE, a citizen of the United States, residing in Philadelphia, Pennsylvania, have invented 5 certain Improvements in Bag Holders, of which the following is a specification.

One object of my invention is to provide an improved bag holder which can be used with advantage in laundries, such as "wet 10 wash" laundries, the structure being such that bags can be quickly secured in position with their mouths wide open to allow clothes to be inserted therein.

Another object is to make my improved 15 bag holder of a strong and durable structure and to prevent the accidental falling of the bag while being filled.

A further object is to so construct my improved bag holder that it will reduce to a 20 minimum possible injury to the bags.

These objects and other advantageous ends 25 which will be set forth hereinafter I attain in the following manner, reference being had to the accompanying drawings in which—

Figure 1 is a side elevation of my improved bag holder,

Figure 2 is a top plan view of said holder,

Figure 3 is an end elevation of the same, 30 Figure 4 is an enlarged section taken on the line 4—4 of Figure 1,

Figure 5 is a section taken on the line 5—5 of Figure 1,

Figure 6 is a side elevation showing a 35 modification in the position of certain of the controlling elements,

Figure 7 is a section taken on the line 7—7 of Figure 6, and

Figure 8 is an enlarged fragmentary view 40 showing certain of the features of my invention in a different position from that shown in the other figures.

Referring to the drawings and particularly to Figures 1, 2, 3, 4, 5 and 8, 9^a represents a base preferably made in the form of a plate. The top of the base 9^a, adjacent one end, supports a standard 9; said standard including a hollow supporting column 10, which is secured to the base 9^a by any 45 suitable means, and a supporting post 11 which telescopically fits within the column 10. The post 11 can be adjusted vertically within the column 10 and secured in its adjusted position by a clamp screw 12.

55 A head piece 13 is secured to the post 11 and has a transverse or substantially T-

shaped top 14. The outer ends of the top 14 have under-cut channels 15 in which arms 16 are mounted. These arms are preferably made of strip spring steel so that their 60 free portions will slightly flex toward each other when the bag is stretched as will be described hereinafter. Furthermore, the arms can be secured in various adjusted positions, horizontally by set screws 17. 65

The arms 16 preferably have outer terminals 18. These terminals include under-cut notches 19 located between fingers 20 and 21.

An arcuate stretching head 22 extends 70 transversely between the arms 16 and has channels 23 through which the arms 16 extend so that the stretching head can slide lengthwise on said arms as rails. The top of the stretching head has an overhanging arcuate flange 24 as clearly shown in Figures 1, 3, and 5.

A flexible cable 25 has one end secured to the stretching head 22 midway between the arms 16, and this cable leads through the hole 26 in the head top 14, then over 80 a pulley 27 and downward adjacent the standard 9. The pulley 27 is rotatably mounted between ears 28 in the head 13 and in alignment with the hole 26 so that the cable 25 can freely pass through the hole 26 and downward over the pulley 27. The opposite end of the cable 25 is secured to a treadle 29. This treadle has a portion 30 slidable vertically in a slot 31 in a guide device 32; the latter being secured to the 90 base 9^a.

A hoist plate 33 has a collar 34 at one end arranged midway between the sides. This collar fits loosely around the column 10 and, owing to the weight of the hoist plate, normally binds against the column. The column 10 has a cut-out portion 35 in which is positioned a pulley 36; the pulley being 95 rotatably mounted on a bolt 37.

A cable 38 has one end connected to the hoist plate near the column 10 and passes over the pulley 36 and through the cut-out portion 35. The opposite end of the cable 35 is attached to a treadle 39. The treadle 39 has a portion 40 vertically slidable in a slot 100 41 in the side of said guide device.

The guide device can be cast and, as illustrated, is secured at the top by the bolt 37; the lower portion of the guide device being secured to the bottom of the base 9^a. 110

In the use of the device, when it is desired to attach a bag and to hold the bag with its

- mouth full open, the upper end of the bag is moved between the arms and the extreme top of the bag is turned downward so as to engage within the notches 19 of the terminal ends of the arms. The opposite portion of said turned end of the bag is then turned downward around the flange 24 of the stretching head 22 so that a part of said end of the bag will engage under the flange 24.
- 10 The workman then places his foot upon the treadle 29 and pushes it downward. This action will move the stretching head 22 away from the terminal ends of the arms 16 and the bag will be stretched at its mouth.
- 15 This stretching action will also cause the arms 16 to flex or bend into frictional holding engagement with the stretching head and the bag will be held securely with its mouth full open. In Figure 1, I have illustrated a
- 20 bag 42 in dot-and-dash lines. Some laundry bags are made of tough, thick cloth such as exceptionally heavy duck or canvas and to guard against the accidental movement of the stretching head
- 25 when such bags are being filled, I provide the under portions of the arms 16 with teeth 16^a which form shoulders for engagement with the free end of a strip spring latch 16^b said latch at one end being secured to the head.
- 30 I provide the spring latch 16^b with a recess 16^c adjacent its free end as clearly shown in Figure 8. A handle 16^d has a portion 16^e which in cross section is longer than it is thick. This portion 16^e rests in the recess
- 35 16^c and allows the free end of the spring latch to engage against one of the shoulders of the teeth 16^a as shown in Figure 1 of the drawing thereby locking the stretching head to the arms. To remove said end of the
- 40 spring latch from the teeth 16^a it is merely necessary to turn the handle a quarter turn into the position shown in Figure 8 and the portion 16^e will serve as a cam by pressing against the under part of the stretching head
- 45 and the bottom of the recess 16^c and will cause the spring latch to be flexed and withdraw the free end thereof from the teeth 16^a. Thus a workman when attaching a bag can move the handle 16^d into the position shown
- 50 in Figure 8, then operate the treadle 29 to move the stretching head to stretch the mouth of the bag into an open position and, when the mouth of the bag is properly stretched, the workman, by a simple movement of the handle 16^d into the position shown in Figure 1, can cause the latch 16^b to lock the stretching head to the arms 16 and thereby guard against accidental movement of the stretching head even though the material of
- 55 the bag is thick and comparatively stiff. I have also shown a set screw 43 which is screwed through a tapped hole in the stretching head to bind against the arm for holding the stretching head against movement relatively to the arms 16. However,

the handle 16^d can be more easily moved and is preferable for quick action when it is desired to lock the stretching head to the arms 16.

If the bags contain any material when they are brought to the holder which requires the supporting of the bottom of the bag while the top is being attached, the hoist plate 33 can be raised by depressing the treadle 39. If it is desired to lower the hoist plate it is merely necessary for the workman to place his foot upon the extension 44 of the hoist plate so as to release the jamming action between the hoist plate and the column 10. The hoist plate will then fall to a lower position.

In the actual use of the holder as above described and set forth it has been found that bags can be quickly and securely attached and held in position with their mouths wide stretched and at the same time there are no parts which will pierce or injure the bags.

Furthermore, laundry bags are very often provided with draw-strings or ropes at their open ends and these draw-strings are usually enclosed in a hem. My improved holder is adequately capable of holding such bags since the space between the flange 24 and the tops of the arms 16 allows the enclosed draw-strings with their housing portions to be freely placed thereunder and it is practically impossible for the bags to become accidentally detached.

In some instances where it is desired or necessary that the operator stand in front of the holder to apply and remove the bags, it is preferable that the treadle mechanism be placed adjacent the front of the holder and in Figures 6 and 7, I have illustrated an arrangement whereby the operator can stand in front of the arm terminals during the working of the stretching mechanism.

Referring to Figures 6 and 7 of the drawings, I have illustrated the guide device 32^a secured to the base 8^a adjacent the front and near one corner. Cables 25^a and 38^a are led from the treadles 29^a and 39^a downward under the base plate so that a workman by operating the treadle 29^a can move the stretching head and by operating the treadle 39^a can move the hoist plate. With the exception of providing additional pulleys 46 at the top of the guide device and allowing the cables to extend under the base plate, the structure is similar to that described in connection with Figures 1 to 5 inclusive and I have, therefore, given similar parts corresponding reference characters.

Having thus described my invention, what I claim as new and desire to secure by Letters Patent is:—

1. In a bag holder, means providing undercut notched portions spaced apart and

downward over and into which parts of the mouth of a bag can be turned after the bag has been moved horizontally therebetween; and a transversely extending stretching head movable toward and from a plane passing through said undercut notched portions.

2. In a bag holder, means providing undercut notched portions spaced apart over 10 and into which parts of the mouth of a bag can be turned; and means having a transversely extending overhanging flange, said flange being movable toward and from a plane passing through said undercut notched 15 portions.

3. In a bag holder, means providing rails and undercut notched portions spaced apart over which parts of the mouth of a bag can be turned downwardly; and a stretching 20 head slideable on said rails toward and from a plane passing through said undercut notched portions.

4. In a bag holder, means providing rails and portions spaced apart over which parts 25 of the mouth of a bag can be turned; a stretching head slideable on said rails; and a treadle connected to and operative to slide said head on the rails whereby the bag can be stretched in the direction of 30 the length of the rails by the action of the foot of an operator.

5. In a bag holder, means providing rails and portions spaced apart over which parts 35 of the mouth of a bag can be turned; a stretching head slideable on said rails; a treadle connected to and operative to slide said head on the rails whereby the bag can be stretched in the direction of the length of the rails by the action of the foot of an 40 operator; and manually operative means for locking the stretching head to the rails after the head has been moved into its stretching position.

6. In a bag holder, means providing rails and portions spaced apart over which parts 45 of a bag can be turned; a stretching head slideable on said rails; a treadle connected to and operative to slide said head on the rails whereby the bag can be stretched in the direction of the length of the rails by 50 the action of the foot of an operator; and means providing an adjustable support for said rails whereby the rails can be adjusted in the direction of their lengths relatively 55 to the stretching head without affecting the treadle connection, thereby rendering the device quickly adjustable.

7. In a bag holder, a standard; arms supported by said standard and having portions for holding parts of the mouth of a 60 bag; a stretching head slidably supported on said arms; a cable attached to said stretching head; means providing a guide for said cable whereby a portion thereof will lead from said stretching head in substantially 65 the path of movement of said stretching head on the arms and another portion of said cable will lead downward; a guide device; and a treadle movable on said guide device and connected to said lat- 70 ter portion of the cable.

8. In a bag holder, means providing a row of teeth; a stretching head movable relatively to said means; a latch carried by said stretching head and movable into and 75 out of holding engagement with said teeth; and a member having a cam portion operative to move said latch out of holding engagement with said teeth.

In testimony whereof, I have signed my 80 name to this specification, in the presence of two subscribing witnesses.
